US00D983140S

(12) **United States Design Patent** (10) **Patent No.:** **US D983,140 S**
(45) **Date of Patent:** **** Apr. 11, 2023**

(54) **FOLDABLE WIRELESS CHARGER**

(71) Applicant: **Shenzhen Autige Technology Co., Ltd,**
Shenzhen (CN)

(72) Inventor: **Ran She**, Shenzhen (CN)

(73) Assignee: **Shenzhen Autige Technology Co., Ltd,**
Shenzhen (CN)

(**) Term: **15 Years**

(21) Appl. No.: **29/868,547**

(22) Filed: **Dec. 6, 2022**

(51) **LOC (14) Cl.** **13-03**

(52) **U.S. Cl.**

USPC **D13/108**

(58) **Field of Classification Search**

USPC D13/103, 107, 108, 118, 119, 183;
D14/240, 251, 253, 356, 358, 432, 433,
D14/434, 447

CPC H02J 15/00; H02J 7/0044; H02J 7/0049;

(57) **CLAIM**

The ornamental design for a foldable wireless charger, as shown and described.

DESCRIPTION

FIG. 1 is a front, right and top perspective view of a foldable wireless charger showing my new design;

FIG. 2 is a rear, right and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is front and left and top perspective view thereof, shown in a first configuration of use;

FIG. 10 is front and left and top perspective view thereof, shown in a second configuration of use; and,

FIG. 11 is front and left and top perspective view thereof, shown in a third configuration of use.

The broken lines in the figures illustrate portions of the foldable wireless charger that form no part of the claimed design.

1 Claim, 11 Drawing Sheets
